UNITED STATES PATENT OFFICE.

EMIL STAHELIN, OF CHICAGO, ILLINOIS, ASSIGNOR TO SHURLOX AWNING AND SHADE COMPANY, OF CHICAGO, ILLINOIS, A CORPORATION OF ILLINOIS.

AWNING.

Application filed October 18, 1924. Serial No. 744,351.

This invention relates to improvements in awnings and particularly to awnings which are lowered and elevated by means of a cord. One object of the invention is to arrange such an awning and its support so that it can be dependably operated under all conditions, and another object is to simplify the mechanism for supporting and operating the awnings. Other objects of the invention will 10 be apparent from a consideration of the accompanying drawings and the following description thereof:

Of the drawings Fig. 1 is a front elevation of an awning and the operating mechanism thereof; Fig. 2 is an enlarged side elevation of the awning; Fig. 3 is an enlarged detail elevation of the operating mechanism and support of the awning, showing in dotted lines the relative positions of the parts 20 when the awning is being raised or lowered; Fig. 4 is a side elevation of a modification of the awning and support; and Fig. 5 is another modified form of the operating mechanism.

The awning, as shown by the drawings herein, is fixed to the window sill 10 by means of a bracket 11 and guide rods 12, one end of each rod being fixed to the sill and the other end being held in by the lugs 13 of 25 the bracket 11. Slidably and rotatably mounted on the rods 12 are brackets 14 to the flanges 15 of which are pivoted bars 16, the outer ends of the bars 16 supporting a rod 17 to which the lower end of the awning 30 fabric 18 is fixed. From the rod 17 the fabric 18 normally extends upwardly and towards the window and passes under a rod 19, supported by the brackets 20 which are fixed to the window sill. The fabric then passes 35 upwardly and is fixed to a roller 21. The roller 21 is rotatably mounted by means of brackets 22 fixed to the window sill. A reel 23 is fixed to, and concentric with, one end 40 of the roller 21, and an operating cord 24 has one end fixed to the reel 23 and is wound around the reel sufficiently, and then passes directly downwardly to a point where it may 45 be conveniently reached by the operator of the awning. The weight of the bars 16, the rod 17, and the awning fabric 18 will tend 50 to rotate the roller 21 and thus to wind up the cord on the reel. But if the lower end of the cord is fixed in any manner the awning will remain supported, and may be thus

maintained at any desired position. Any 55 suitable means may be used for holding the lower end of the cord. I prefer to pass it around a pulley 25 supported by a bracket 26 and then to a cleat 27 about which the cord may be wrapped. 60

I also provide means for firmly holding each of the bars 16 against upward movement when the awning is in place. These means comprise a pawl 28 pivoted to each of the bars 16. These pawls are adapted to 65 coact with teeth 29 fixed to the flange 15 of the bracket 14. When the awning is in the position shown by Fig. 2, it is obvious that the ends of the bars 16 can not be pulled upwardly; hence, by pulling tightly on the 70 cord 25 the awning will be held firmly in place, and the particular angle of the bars 16 will depend upon the particular tooth 29 with which the pawls 28 coact.

In order to suitably operate the bars 16, in 75 adjusting the position of the awning, or to remove the entire awning from the front of the window, the shape of the pawls 28 is such that when the cord 24 is loosened and the bars 16 are turned downwardly, the pawls 80 28, after passing away from the teeth 29, will turn downwardly as indicated at 30 in the Fig. 3. The bars 16 may then be pulled upwardly to a vertical position. When in this position the force of gravity acting on 85 the pawls will turn them to the position indicated by Fig. 3. If now the cord 24 is again loosened the force of gravity will rotate the upper ends of the bars 16 downwardly and the pawls will take positions such as 90 are indicated by the full lines in Fig. 3; and, obviously, when the pawls thus coact with any of the teeth 29 the bars will be held from upward movement by the pawls; so that the bars may be held at any angle which may be 95 desired so long as the pawls coact with the teeth. It is usually desired to hold the bars at substantially right angles in the position indicated in Fig. 1, but the outer ends of the bars 16 may be supported materially higher 100 if desired.

In order to remove the entire awning fabric away from in front of the window, the brackets 14 are slidably mounted on the rod 12, and, by pulling downwardly on the cord 105 24 after the bars 16 are substantially vertical, the awning fabric will be rolled up on the roller 21 until the ends of the rods

reach the roller, when, if the various parts are properly proportioned, the awning fabric will be entirely above the window. From this position, in order to replace the awning, it is necessary only to release the cord 24 and the weight of the various parts will force the brackets 14 downwardly until they rest upon the flanges 13, when the bars 16 will rotate outwardly and downwardly to 10 the desired positions.

In order that the bars 16 will rotate downwardly from the elevated positions the arrangement is such that these bars never reach a vertical position; and to prevent this 15 any suitable means may be taken. I prefer to provide lugs 41 fixed at the back of the pawls 28, and these lugs and the pawls themselves strike against the brackets 14 when the arms 16 have been raised sufficiently.

20 In order to prevent any improper coaction of the pawls 28 with the flanges 15 or the teeth 29, as the awning is being lowered, I provide lugs 42 extending upwardly from the flanges 15, so that, as the arms 16 are 25 lowered, the ends of the pawls 28 will strike upon the lugs 42 and prevent any possibility of the pawls striking on the upper surfaces 43 of the flanges 15 or the upper teeth and thus preventing downward movement of the 30 bars 16.

Fig. 4 illustrates a modification of my awning support. In this case the brackets 50, which take the place of the sliding brackets 14, are permanently fixed to the window sill, the rods 12 are dispensed with. By operating the cord 51 the bars 52 may be 35 elevated or lowered in the same manner as has been described herein with reference to the bars 16. The pawls 53 coact with teeth 54 in the same manner as the coaction of the pawls 28 with the teeth 29 when the bars 52 are elevated to substantially the vertical position, however, the awning as a whole can 40 not be elevated, as is the case with the awning illustrated in Fig. 1. A further modification is to increase the length of the bars 52, and, if desired, the outer ends of these 45 bars will rise substantially to the roller 56 and the awning may thus be removed entirely or substantially from in front of the window. As a further modification I provide means for varying the length of the bars 52. These means comprise sockets 56, which are pivoted to the brackets 50, and 50 sockets 57 which are fixed to the rod 58. The length of the bars may then be varied 55 as desired by mounting a rod or pipe 59 in the sockets 56 and 57. In order to vary the length of the bars 52 it is necessary only to 60 insert in the sockets bars 59 of the desired length.

Fig. 5 illustrates a further modification which can be used with either type of mechanism. This comprises a toothless surface 65 60 on the flange 61 with which the pawl 62

coacts. The surface 60 may be smooth, or roughened as much as desired to prevent slippage; but in either case the adjustment is more sensitive than with the teeth on the flange; and this arrangement obviates the 70 necessity of having the pawls coact with corresponding teeth so that the bars 16 will be at the same angle.

I claim as my invention:

1. The combination of an awning fabric 75 and its support, including a bracket, an arm pivotally connected to said bracket, a pawl pivotally connected to said arm and normally extending inwardly and upwardly from its pivoted end, holding means mounted on said bracket with which the end of said pawl is normally engaged, and from which it is disengaged by the lowering of the arm, said pawl being arranged to be forced downwardly by gravity when so disengaged from said holding means.

2. The combination of an awning fabric and its support, including a bracket and an outwardly swinging arm pivoted to said bracket, a brace pivotally connected to said arm and normally extending inwardly and upwardly from its pivoted end, holding means mounted on said bracket with which the end of said brace is normally engaged and from which it is disengaged by the lowering of the arm, said brace being arranged to be forced downwardly by gravity when so disengaged from said holding means; and means for bringing into engagement said brace and holding means when said arm has 100 been raised to a predetermined position and then lowered to its normal position.

3. An awning, including a support, an outwardly swinging arm operatively connected with said support, a pawl pivotally connected to said arm, and a ratchet fixed to said support with which the outer end of said pawl engages when the awning is lowered to its normal position, said pawl being disengaged from said ratchet when said arm is lowered below its normal position and then raised.

4. The combination of an awning fabric and its support, including a bracket and an outwardly swinging arm, of a pawl pivoted to said arm, a ratchet fixed to said bracket with which said pawl engages when in its normal position, said pawl being disengaged from said ratchet when said arm is lowered and then raised to a substantially vertical 110 position, and means for preventing said pawl from becoming engaged with said ratchet as said arm is being lowered.

5. A frame for an awning fabric, said frame comprising a bracket, an arm having one end pivotally connected with said bracket, a flange projecting from said bracket, a brace pivoted to said arm, and adapted normally to coact with said flange to prevent upward rotation of said arm, said brace ar- 125

ranged to pass out of coaction from said flange when said arm is lowered below its normal position, whereby said arm may be moved upwardly until substantially vertical.

5 6. A frame for an awning fabric, said frame comprising a bracket, an arm having one end pivotally connected with said bracket, a flange projecting from said bracket, a brace pivoted to said arm, and adapted normally to coact with said flange to prevent upward rotation of said arm, said brace arranged to pass out of coaction from said flange when said arm is lowered below its normal position, whereby said arm may be moved upwardly until substantially vertical; and means to prevent coaction of said brace with said flange when said arm is being lowered to its normal position.

7. In an awning a bracket, an arm pivoted to said bracket and normally extending outwardly, one end of an awning fabric fixed to the outer end of said arm, a roller mounted above said bracket, the other end of said fabric being fixed to said roller, means for rotating said roller, means for preventing upward rotation of said arm when said arm is in its normal position, said means being arranged to be rendered inoperative when said arm is lowered below its normal position, and is then raised to a substantially vertical position; said bracket being slidably mounted for vertical movement.

8. An awning support, comprising a bracket adapted to be fixed to a window sill, said bracket having a flange projecting therefrom, an arm pivoted to said bracket, a brace pivoted to said arm, and normally coacting with said flange to prevent upward rotation of said arm, said brace projecting inwardly towards said bracket; and a lug projecting upwardly from the upper edge of said flange and adapted to prevent the said brace from coacting with said flange when said arm is

being lowered from a substantially vertical position. 45

9. An awning support comprising a bracket, having a flange, an arm pivoted to said flange, a brace pivoted to said arm, said brace and flange having surfaces which normally coact with each other to prevent upward rotation of said arm when said arm is moving downwardly from a position above horizontal. 50

10. An article of manufacture comprising a member having a projection and being adapted to be fastened to a frame, an arm pivoted to said member, means pivoted to said arm and adapted to coact with said projection to prevent upward movement of said arm, and means mounted on the free end of said arm for receiving radially one end of a bar. 55

11. An awning support comprising a bracket, having a flange, an arm pivoted to said flange, a brace pivoted to said arm, said brace and flange having surfaces which normally coact with each other to prevent upward rotation of said arm when said arm is moving downwardly from a position above horizontal; and means fixed to said brace for 60 limiting the upward rotation of said arm. 70

12. An article of manufacture comprising a member having a projection and being adapted to be fastened to a frame, an arm pivoted to said member, means pivoted to said arm and adapted to coact with said projection to prevent upward movement of said arm, and means mounted on the free end of said arm for receiving one end of a bar coaxially with said arm, and means fixed to 75 said brace for limiting the upward rotation of said arm. 80

In testimony whereof, I hereunto set my hand.

EMIL STAHELIN.
